SEVERING APPARATUS

Frank Lombardo, Kansas City, Mo.

Application May 3, 1943, Serial No. 485,469

4 Claims. (Cl. 164—38)

This invention relates to severing apparatus of the character employed in factories where fabric bags or the like are produced through the employment of power sewing machines and where such bags are interconnected by a length of thread or cord which must be severed before the bag is reversed and made ready for use.

One of the primary objects of this invention is the provision of severing apparatus that forms a part of a bag-receiving platform and which functions through the combined use of the force of gravity exerted upon the material being severed and through the power driven mechanism embodying the invention.

A further aim of this invention is the provision of severing apparatus of the aforementioned character having a specially disposed cutting element, the sharpened edge whereof intersects a face of the specially designed support in such fashion as to require the material being severed to travel along a length of the sharpened edge as the material drops through the action of gravity.

This invention has for an even further object to provide severing apparatus for thread or the like, that comprises a cutting element, means for directing the material being severed across the cutting edge of the said element, and power driven mechanism for relatively moving the said cutting element and the directing means.

To the present time, conventional methods of manufacturing bags that must be stitched by power machines, has involved the step of manually severing the chain stitching between successive bags as they pass from the sewing machines. The bags are stacked by hand on a conventional platform and as the workers so stack the bags, a knife or scissors is used to cut the stitching joining the bags. The danger involved, time consumed, and effort wasted are all elements of the problem to which severing apparatus embodying this invention is an answer.

In the preferred embodiment, severing apparatus contemplated is attached directly to the platform upon which the bags are stacked and functions automatically as the bags are being placed, and as soon as the interconnecting stitching or thread is drawn over a certain portion of the cutting element support. Thus, the operator need only place the individual bags one upon another, on the platform and guide the interconnecting stitching to place over the severing apparatus, whereupon the threads will be cut without further attention on the part of the worker.

Two forms of the invention are illustrated in the accompanying drawing, wherein:

Fig. 1 is a perspective view of a conventional platform having mounted thereon, severing apparatus made in accordance with the present invention.

Fig. 2 is an enlarged side elevational view of the severing apparatus.

Fig. 3 is an edge elevational view thereof.

Fig. 4 is a fragmentary detailed sectional view taken on line IV—IV of Fig. 3.

Fig. 5 is a fragmentary sectional view taken on line V—V of Fig. 2.

Fig. 6 is an enlarged detailed fragmentary sectional view taken on line VI—VI of Fig. 2.

Fig. 7 is a fragmentary side elevational view 15 of a severing apparatus made to embody a modified form of the invention; and

Fig. 8 is a cross sectional view taken on line VIII—VIII of Fig. 7.

While the severing apparatus about to be described by reference to the accompanying drawing, is particularly useful in severing the chain stitching 10, interconnecting fabric bags 12, it must be understood that the apparatus may be employed to advantage in a number of ways.

For purpose of illustration, however, the severing apparatus is shown mounted upon a platform 14, the nature of which is conventional and whereupon is stacked a number of bags 12 as they are made ready for the next step in the manufacture thereof. The bags have just left the sewing machines and the stitching 10 remains to be severed.

The "stacker" usually cuts the interconnecting stitching 10 by a manual operation, but as has been heretofore indicated, this method is unsatisfactory. To automatically sever stitching 10, therefore, the severing apparatus made to embody the preferred form of the invention, and shown in Figs. 1 to 6 inclusive, is mounted directly upon platform 14 through the medium of a bracket 16 and bolts 18 having wing nuts 20 thereon. These bolts 18 may remain in place on platform 14 and wing nuts 20 merely adjusted to allow transfer of the entire severing apparatus from one point of operation on a platform 14, to another.

Obviously, the apparatus is mounted near one corner of the platform where stitching 10 may be introduced to slot 22 of support 24. This support 24 has a cavity 26 formed therein for the reception of the cutting element 28, a portion of which is exposed by slot 22.

Cutting element 28 is mounted for rotation as detailed in Fig. 5, in that it is carried by a shaft 30 journaled in bearings 32 and provided with a wheel 34 over which passes a belt 36. A motor 38 has a pulley wheel 40 on the shaft 42 thereof,

and the endless belt 36 passes over pulley wheel 40 to complete the means by which power is imparted to cutting element 28.

Support 24 houses a portion of the length of belt 36 and may be extended to house even wheel 40 and that portion of shaft 42 extending beyond motor 38. A bracket 44 secures together support 24 and motor 38.

Slot 22 is especially formed in that it extends downwardly and at an angle to the vertical to intersect a portion of the length of the sharpened cutting edge 46 of element 28. Downwardly and outwardly inclined faces 48 formed on support 24 project laterally to each side of cutting element 28 and when stitching 10 is dropped into slot 22, the faces of support 24 adjacent to cutting element 28 will guide the material to be severed (10), toward cutting element 28 where a portion of its sharpened cutting edge will wipingly engage the material to quickly sever the same. Motor 38 constantly operates to drive cutting element 28 and because cavity 26 communicates with slot 22 in the fashion shown in Fig. 2, a shearing action will also occur if the cutting element 28 has not completely severed stitching 10 before it is drawn tightly against the edge of support 24 forming one side of slot 22.

The downward pull exerted upon stitching 10 which is to be severed, is established through the action of gravity upon adjacent bags 12. As the operator places one bag 12 upon platform 14, the succeeding bag 12 disposed to the opposite side of the severing apparatus will draw stitching 10 against cutting element 28. No pressure need be exerted by the operator.

In the modified form of the invention shown in Figs. 7 and 8, support 100 is of a similar nature to that illustrated in Figs. 1 to 6 inclusive, but the cutting element 102 is a straight piece having a sharpened edge 104 that intersects slot 106. The drive belt 108 in this instance, rotates a pair of spaced discs 110 in the periphery of each of which is formed a number of notches 112. These notches engage stitching 10 and draw the same across a portion of the cutting edge 104 of element 102. The two discs 110 are disposed with respect to element 102 as illustrated in Fig. 8, that is, the sharpened marginal edge of element 102 lies between discs 110.

The severing apparatus made in accordance with the modified form of the invention operates in substantially the same manner as set down above with respect to the apparatus illustrated in Fig. 1. The material to be severed is dropped into slot 106 and through the action of gravity said material will move toward rotating discs 110, whereupon notches 112 will assist gravity in drawing the material to be severed across a portion of the length of cutting edge 104.

It is understood that severing apparatus having physical characteristics different from those illustrated and described might be produced without departing from the spirit of the invention or scope of the appended claims.

Having thus described the invention, what is claimed as new and desired to be secured by Letters Patent is:

1. Severing apparatus for the interconnecting threads of stitched fabric bags or the like, comprising a cutting element having a sharpened edge; a slotted support for the element; and means for drawing the threads across the sharpened edge of the cutting element when the threads enter the slot of the support, said slot of the support and the sharpened edges intersecting each other at an acute angle, said angle being positioned with its vertex at the lowermost point to cause the action of gravity upon the fabric bags to assist in drawing the threads into said vertex against the sharpened edge.

2. Severing apparatus of the character described comprising a cutting element; a slotted support for said element, the slot of said support having an inclined face intersecting the cutting element at an acute angle, said angle being positioned with its vertex at the lowermost point to cause material entering the slot and following said inclined face to move under action of gravity into said vertex for severance by the cutting element; and means for supplementing the action of gravity to force the material into said vertex.

3. Severing apparatus of the character described comprising a cutting element; a slotted support for said element, the slot of said support having an inclined face intersecting the cutting element at an acute angle, said angle being positioned with its vertex at the lowermost point to cause material entering the slot and following said inclined face to move under action of gravity into said vertex for severance by the cutting element; and rotating means for supplementing the action of gravity to force the material into said vertex.

4. Severing apparatus of the character described comprising a cutting element; a slotted support for said element, the slot of said support having an inclined face intersecting the cutting element at an acute angle, said angle being positioned with its vertex at the lowermost point to cause material entering the slot and following said inclined face to move under action of gravity into said vertex for severance by the cutting element; means for supplementing the action of gravity to force the material into said vertex, said means comprising a rotatable wheel having notches in its periphery; and drive means for rotating said wheel.
